(57) **CLAIM**

The ornamental design for an oral cotton swab, as shown and described.

DESCRIPTION

FIG. 1 is a perspective view of an oral cotton swab showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is an enlarged view of the encircled area 8 of FIG. 1. The broken lines shown in the figures depict portions of the oral cotton swab that do not form part of the claimed design. In FIGS. 1 and 8, the broken lines depict the enlarged view boundaries that do not form part of the claimed design.

1 Claim, 5 Drawing Sheets
